UNITED STATES PATENT OFFICE.

WILLIAM W. BALDWIN, OF CLEVELAND, OHIO, ASSIGNOR TO THE CLEVELAND CO-OPERATIVE STOVE AND HOLLOW WARE FOUNDRY COMPANY, OF SAME PLACE.

DESIGN FOR A BEDSTEAD.

SPECIFICATION forming part of Design No. 28,769, dated May 31, 1898.

Application filed June 4, 1897. Serial No. 639,478. Term of patent 7 years.

To all whom it may concern:

Be it known that I, WILLIAM W. BALDWIN, a citizen of the United States, residing at Cleveland, in the county of Cuyahoga and State of Ohio, have invented and produced a new, useful, and original Design for a Bedstead, of which the following is a full, clear, and exact description, reference being had to the accompanying drawing, forming a part hereof.

The drawing is a perspective view of a bed embodying my design.

The leading features of the design consist of a bedstead whose side rail presents to the eye an upper portion of more or less ornate open-work design and a lower portion having a substantially plain surface. The open or

ornate features of the upper part cause a pleasing contrast to the solid and plain appearance of the lower part.

In the drawing, B represents the lower plain part of the side rail of the bed, and C represents the upper open-work part thereof.

Having described my invention, what I claim as new, and desire to secure by Letters Patent, is—

The design for a bedstead, substantially as herein shown and described.

In testimony whereof I affix my signature in presence of two witnesses.

WILLIAM W. BALDWIN.

Witnesses:

E. L. THURSTON,
ALBERT H. BATES.
